UNITED STATES PATENT OFFICE

RICHARD THURM, OF SAGINAW, MICHIGAN, ASSIGNOR TO BAKER PERKINS COMPANY, INCORPORATED, OF SAGINAW, MICHIGAN, A CORPORATION OF NEW YORK

TUBULAR BURNER

Original application filed October 15, 1925, Serial No. 62,511. Divided and this application filed January 31, 1928. Serial No. 250,847.

The invention relates to burners for illuminating gas, producer gas, water gas, vaporized oils and similar fuels, and it pertains particularly to burners of the long tubular type which are employed for burning mixtures of gaseous fuels and air in atmospheres which are substantially free from oxygen, such, for example, as baking ovens.

When the ordinary long tubular type of burner is located so that the combustion at its outlet takes place in a more or less confined space in an atmosphere that is substantially free from or at least deficient in oxygen and raised to a comparatively high temperature, there is liability to objectionable and somewhat dangerous backfiring and explosions.

The principal object of the present invention is to provide a burner so constructed as to prevent such backfiring and explosions, and to insure a continuous and substantially uniform combustion throughout the length of the burner.

With these and other objects in view, the invention comprises the novel and improved features, constructions and combination of parts hereinafter described and particularly pointed out in the claims, the advantages of which will be clearly understood and appreciated by those skilled in the art.

This application is a divisional application based upon certain subject-matter contained in a prior application, Serial No. 62,511, filed October 15, 1925, by Richard

Thurm and Eugene Oscar Engels.

The invention will be clearly understood from the accompanying drawings illustrating the invention in its preferred forms and the following detailed description of the construction therein shown.

In the drawings—

Figure 1 is a view in side elevation of a burner showing its arrangement in the chamber of a baking oven and its connection to the means for supplying fuel thereto;

Figure 2 is a vertical sectional view through the burner taken on the line 2—2 of Figure 1;

Figure 3 is a detail top plan view on an enlarged scale of a section of the burner;

Figures 4 and 5 are detail views in eleva-

tion showing one means by which the discharge of fuel from the burner is controlled;

Figures 6 and 7 are horizontal sectional views showing different modified forms of fuel discharge controlling means; and

Figures 8 and 9 are views in side elevation showing still further modified forms of discharge controlling means.

In the illustrated embodiment of the invention, the burner includes a suitable fuel chamber to which combustible fuel is supplied from a suitable conduit, which preferably extends substantially throughout the length of the fuel chamber. This conduit is supplied with combustible fuel from a suitable fuel main to which the fuel is supplied from a mixing device and which, in turn, has connection with suitable means for supplying the different elements of which the fuel is composed. From the fuel chamber, the fuel is discharged and burned at the point of discharge.

In the accompanying drawings, the burner is designated by the reference character 10 and as shown in Figure 2, said burner includes a chamber which consists of a tubular member 19 substantially circular in cross-sectional form. This tubular member 19 is provided with an elongated slot 21, the length of which is determined by the length of the flame desired and which, in the present instance, is shown as extending throughout the major portion of the length of said tubular member.

In this type of burner, a conduit 20 is employed and this conduit extends throughout substantially the entire length of the chamber formed by the tubular member 19, as indicated by dotted lines in Figure 1. This conduit 20 is semi-circular in cross-section and as shown in Figure 2, is located in the lower portion of the tubular member 14 with its plane wall positioned upwardly. This construction provides a fuel chamber 25 in the tubular member 19. Suitable discharge openings such, for example, as the perforations 26 are provided in the straight wall of the conduit 20 and these discharge openings serve to permit the fuel to pass from the conduit 20 into the fuel chamber 25 in the tubular mem-

ber 19. By this construction, a uniform pressure of fuel is maintained in the chamber 25. Fuel is supplied to the conduit 20 by means of a suitable pipe 11 controlled by a valve 13 and connected to a fuel main 12 for supplying combustible fuel. The fuel is supplied to the fuel main 12 from a suitable mixing device 14 to which the elements of the fuel are supplied separately in any desired manner.

10 Thus, it will be seen that the fuel passing from the pipe 11 into the conduit 20 is discharged therefrom through the openings 26 and passes into the chamber formed by the tubular member 19. The fuel is discharged from the chamber formed by the tubular member 19 through the elongated slot 21 and as the fuel issues therefrom, it is ignited or burned to provide the flame of the burner.

15 20 The tubular member 19 is provided with suitable means constructed to form a plurality of relatively long passageways through which the fuel passes in its discharge from the chamber of the tubular member 19.

25 A suitable structure is positioned within the elongated slot 21 to secure this result. As shown in Figures 3, 4 and 5, this structure comprises two relatively long plates of greater width than thickness which are adapted to be retained in the elongated slot 21 with their adjacent side faces in contact with each other. These two plates are designated by the reference characters 22 and 29 in the accompanying drawings, and as will be noted from Figure 3, the adjacent faces of these plates are transversely grooved as indicated at 31 and 32 respectively. It will be noted that the transversely-extending grooves of each 30 of the plates 22 and 29 are spaced with respect to one another and further that the grooves 31 in the plate 22 are of a smaller transverse dimension than the grooves 32 of the plate 29, and consequently the intervening spaces between the grooves 31 of the plate 22 will be wider than that between the grooves 32 of the plate 29.

40 As heretofore stated, these plates are positioned with their grooved faces adjacent and the plates may be retained in this position by a plurality of fastening means, such as, for example, rivets 46.

45 The grooved plates 22 and 29 when thus secured together, and secured within the slot 21 of the tubular member 19, provide a series of channels or passages through which the gaseous mixture is discharged from the tubular member in a plurality of individual jets.

50 The channelled structure is positioned in 55 the elongated slot 21 and is retained in position therein by the side edges of the slot which are caused to engage the outer faces of the channelled structure and clamp the same within the slot. This result is obtained by means of bolts extending trans-

versely of the tubular member 19, which bolts are provided with nuts 28, which, when tightened on their respective bolts, cause a contraction of the tubular member 19 and thus results in a clamping of the channelled structure within the elongated slot 21.

60 Additional securing means for the channelled structure may be employed and as shown in Figure 3, this additional means may comprise suitable clamping members 75 such as 47 secured to the outer face of the tubular member 19 at points between its ends and end plates 48 which latter conform in shape to the tubular member and serve to prevent the escape of gas around the ends of the channelled structure. As shown in Figure 3, this structure is slightly shorter than the length of the elongated slot to allow for expansion of the same during operation of the burner.

70 75 In Figure 6 is shown a slightly modified form of channelled structure, in which there are two plates 33 and 34. The plate 34 is provided with a plurality of transversely-extending grooves 35 which are spaced with 80 respect to one another and in forming the channelled structure the plate 34 is placed with its grooved face engaging the smooth face of the plate 33. These plates 33 and 34 may be attached together and secured 85 within the elongated slot 21 and tubular member 19 in the same manner as described in the form of the invention shown in Figure 2.

90 95 In Figure 7, a still further modified form of the invention is shown and in this form 100 a plate 40 is provided in its opposite sides with a plurality of transversely-extending grooves, the grooves of one side being offset or staggered with respect to those of the other side. In forming the channelled structure, this plate 40 is secured between two plates 37 and 38, each having a smooth face engaging the plate 40, this plate together with the grooves of the plate 40 forming a plurality of channels. This entire structure 105 is secured in the elongated slot 21 of the tubular member 19 in the same manner as in the other forms of the invention. This type 110 of channelled structure will provide a double burner, that is, a double row of jets through 115 which the fuel is discharged.

120 In the further modified form of the invention shown in Figure 8, a plate 41 is provided with a plurality of diagonally-extending grooves 42. In the preferred construction, this plate is assembled with a second plate of corresponding shape and size having a smooth face, the smooth face of the second plate being placed in contact with the grooved face of the plate 41. These two plates are inserted in the slot 21 of the tubular member 19 and are secured in position therein. The grooves 42 thus provide a plurality 125 of channels through which the gaseous mixture is discharged from the tubular member. 130

Figure 9 shows a form of the invention similar to that shown in Figure 8. In the form of the invention shown in Figure 9, the plate 43 is provided with two sets of diagonally-extending grooves 44 and 45, the grooves 44 and 45 intersecting each other as shown. This plate is preferably assembled with a smooth face plate within the slot 21 in substantially the same manner as the plate 41 to provide passages for the discharge of the gaseous mixture from the tubular member.

It is to be understood that a plurality of these burners are employed in a baking oven, and as shown in Figure 1, the burners are supported at their ends in the walls 15 and 16 and between their ends, the burners may be supported by suitable supports such as 17.

The invention is not limited to the particular construction and arrangement of parts of the illustrated embodiments of the invention, but may be embodied in other forms within the scope of the claims.

Having explained the nature and object of the invention and having specifically described the structure embodying the invention in its preferred form, what is claimed is:

1. A burner comprising a relatively long tubular member provided with a slot extending longitudinally thereof, and a plurality of relatively long narrow walls placed face to face and extending along said slot, each of said walls having a series of spaced grooves extending transversely thereof to provide channels through which the fuel is discharged from the tubular member, said grooves being so arranged that the grooves of each wall are opposite the spaces between the grooves of the other wall.

2. A burner comprising a relatively long tubular member provided with a slot extending longitudinally thereof, and a plurality of relatively long narrow walls placed face to face and extending along said slot, each of said walls having a series of spaced grooves extending transversely thereof to provide channels through which the fuel is discharged from the tubular member, the grooves in one wall being wider than the grooves in the other wall, and the grooves in each wall being opposite the spaces between the grooves in the other wall.

3. A burner comprising a relatively long tubular member provided with a slot extending longitudinally thereof, and a plurality of relatively long narrow walls placed face to face and extending along said slot, one of said walls having a series of grooves extending transversely thereof and the other wall having a substantially smooth surface opposite the grooves to provide channels through which the fuel is discharged from the tubular member.

Signed at Saginaw, Michigan, this 25th day of January, 1928.
